NURSING BOTTLE SUPPORT

Charles Cox Bell, Marblehead, Mass.

Application February 3, 1939, Serial No. 254,468

5 Claims. (Cl. 248—105)

My invention relates to devices for supporting nursing bottles and consists, in one aspect, in an improved support by means of which a nursing bottle may be supported directly above the body of an infant lying on its back.

Ordinarily the process of feeding an infant requires that the infant be held in a person's lap, the person feeding the infant using one hand to hold the bottle and the other arm to support the infant. Inasmuch as this process is not only wearisome to the person feeding the child but is also undoubtedly uncomfortable for the child, there has been a long-felt need for a device which would allow the infant to lie flat on its back and take its food from a bottle supported in correct nursing position. Quite often a bottle is supported on a pillow at the side of the infant, but this method is unsatisfactory for the reason that the bottle rolls off the pillow and out of reach of the infant. Furthermore, if the infant changes its position, it can no longer reach the bottle.

Various attempts have been made to devise clamps or supports to replace the pillow in the above-mentioned method. However, these substitutes for the pillow have proved unsatisfactory for several reasons.

The supports heretofore used have been objectionable because they require either that the baby twist its head to one side in order to reach the bottle or that the baby be propped up on its side. Furthermore the baby is entirely free to move with respect to the bottle, and it commonly happens that the infant will roll away from the bottle and not be able to reach it again.

The most important object of my invention is to provide a nursing bottle support whereby the baby can nurse while in a natural and physiologically correct position. My invention also has for its object to provide a bottle holder adapted to be arranged so that the nursing infant is loosely confined within a zone about the bottle so that the infant can choose its own gait and thus avoid colic which often results when an infant is required to hold a nipple in its mouth for extended periods of time. In such cases the infant sucks in air around the nipple in excessive quantities.

An important feature of the invention resides in a novel clamping device which may be adjusted to maintain the bottle in any predetermined position and also allows slight movement of the bottle so that it will respond to the tugs of a nursing infant.

In addition to the advantages resulting from

the attainment of the foregoing objects of my invention, its use involves ancillary advantages. For example, at present it is necessary that some person supervise the feeding of an infant, either holding the infant and the bottle or seeing to it that the infant can reach the bottle at all times when held in a clamp or other support. When my invention is used, it is only necessary to prepare the bottle, place the support over the child, and place the bottle in the support. The infant is then able to carry out the feeding program alone. Thus, a burdened parent is relieved and may devote more time to other duties. The time saving is an important factor, since a nursing infant usually takes from 20 minutes to one half hour to consume a bottle, and from four to six bottles are generally administered each day.

Broadly speaking, my invention comprises a support adapted to be disposed at the side of an infant, a transverse bar secured to the support and projecting above and across the infant, and means on the bar for suspending a nursing bottle substantially above the baby's mouth.

These and other features of the invention will be more readily understood and appreciated from the following detailed description of a preferred embodiment thereof, selected for purposes of illustration and shown in the accompanying drawing, in which:

Fig. 1 is a plan view of a nursing bottle support constructed according to my invention, and

Fig. 2 is a view partly in section and partly in elevation on a line taken transversely of the device, and

Fig. 3 is a plan view of the rubber gasket.

In the preferred embodiment of my invention as illustrated in the drawing an inclined bar 10 of wood or other suitable material is secured at both ends to a pair of identical side supports 12 and 13 which are generally triangular in shape and provided with flat bases adapted to rest on the flat surface of a bed or wherever it may be convenient to place the infant during the nursing period. As shown in Fig. 2 an infant 14 lies beneath the transverse bar 10 on a bed 16, and is covered by bed clothes 17.

The transverse bar 10 is provided with a centrally located aperture 18 having sides perpendicular to the plane of the bar. The aperture 18 is slightly larger than the outside diameter of a standard nursing bottle. In Fig. 2 the device is shown while in use, and it will appear that a nursing bottle 19 is first surrounded by a rubber skirt or gasket 20 which is provided with a cen-

trally located hole considerably smaller in diameter than the diameter of the bottle 19. After the skirt 20 is pulled over the bottle 19, the bottle is thrust through the aperture 18 until the rubber

- 5 gasket 20 engages the sides of the aperture 18 and by wedging action prevents the bottle from being drawn farther through the hole 18. The level of the milk or other substance in the bottle is indicated at 21. The inclination of the bar 10 10 locates the bottle 19 in proper angular position convenient to the nursing child.

It will be apparent that the location of the nipple 22 is determined by the position of the rubber gasket 20 on the bottle 19. That is to say, the nipple 22 can be raised or lowered by changing the position of the gasket 20 either nearer or farther from the upper end of the bottle 19. The bottle 19 is not tightly wedged in the hole 18 but may be twisted or rotated some- 20 what so that it will respond naturally to the tug of the nursing child.

In addition to supporting the nursing bottle in correct nursing position, my invention renders it unnecessary for the feeding to be supervised.

- 25 This is accomplished by reason of the fact that the infant is confined between the side members 12 and 13, and I have found that an infant cannot get so far away from the bottle that it cannot reach it again without assistance. Furthermore, the bottle 19 may be removed from the aperture 18 and inspected if it is desired to ascertain how much milk, or formula, has been consumed by the baby.

While the rubber gasket is convenient and 35 easy to use, I also contemplate the use of any means, such as a coil spring, which will simultaneously hold the bottle frictionally and form an abutment or shoulder on the bottle larger than the diameter of the aperture in the trans- 40 verse member.

- 45 It should be understood that the chief importance of my invention resides in the fact that the nursing bottle is supported above the infant when the latter is substantially prone. While I accomplish this by means of the construction shown in the drawing, it will be apparent that there are many other ways of supporting the bottle in correct nursing position. For example, the side members 12 and 13 might be eliminated 50 and one end of the transverse bar 10 could be clamped to the bars of a crib. The bottle would still be supported in correct nursing position, although the device could then be conveniently

used only in conjunction with a crib, whereas the feeder shown in the drawing may be used whenever there is a flat surface for the bases of the members 12 and 13 to rest upon. In any event, it should be understood that my invention is not limited to the precise construction shown in the drawing but may be practiced with the use of equivalent means within the scope of the appended claims.

Having thus described my invention what I claim as new and desire to secure by Letters Patent of the United States is:

1. A device for feeding an infant, which comprises a pair of supports arranged to be disposed at opposite sides of a prone infant, an inclined transverse member connecting the upper ends of said supports and provided with a centrally located aperture, and a flexible gasket arranged to fit over a nursing bottle and hold it at a predetermined position in the aperture. 20

2. A device for feeding an infant from a bottle which comprises a bar having an aperture, means for supporting said bar above and across the body of an infant, and means arranged to fit over a bottle and hold it in correct nursing 25 position in the aperture in said bar.

3. A device for feeding an infant from a nursing bottle, which comprises an apertured member, means for supporting the member above and across a prone infant, and a rubber ring provided with a central opening smaller than the diameter of a nursing bottle and which frictionally engages and holds a bottle, whereby a bottle encompassed by said ring may be inserted in the aperture of said member and prevented from 30 passing therethrough by the wedging action of 35 said rubber ring.

4. A device for feeding an infant from a bottle which comprises a bar, means for supporting the bar above and across the body of an infant, said bar having an aperture, and a flexible resilient member adapted to maintain a nursing bottle in 40 said aperture in correct nursing position.

5. A device for feeding an infant, which comprises a pair of supports arranged to be disposed at opposite sides of a prone infant, a transverse member connecting the upper ends of said supports and provided with a centrally located aperture, and a flexible gasket arranged to fit over a nursing bottle and hold it at a predetermined 50 position in the aperture. 45
